UNITED STATES PATENT OFFICE.

AUBREY J. GRINDLE, OF CHICAGO, ILLINOIS, ASSIGNEE TO GRINDLE FUEL EQUIPMENT COMPANY, OF HARVEY, ILLINOIS, A CORPORATION OF ILLINOIS.

POWDERED-MATERIAL-FIRING APPARATUS.

Application filed February 4, 1922. Serial No. 534,241.

To all whom it may concern:

Be it known that I, AUBREY J. GRINDLE, a citizen of the United States, residing at Chicago, in the county of Cook and State of Illinois, have invented a certain new and useful Improvement in Powdered-Material-Firing Apparatus, of which the following is a specification.

This invention relates to mechanism for controlling the feed of powdered fuel material, such as powdered coal, so that it will burn efficiently in the apparatus in which it is to be consumed.

The object of the invention is to provide an accurately controlled means for regulating the supply of fuel material deliverable to the burning apparatus for regulating the amount of air delivered to the burning apparatus and for adjusting the respective supplies of air and fuel material to each other.

The invention consists in the mechanism for attaining the foregoing objects which is especially adapted, because of its accuracy of adjustment, to the burning of powdered coal in furnaces or other burning apparatus. It further consists in many other features and details of construction which will be hereafter fully set forth in the specification and claims.

Referring to the drawings, in which like numerals designate the same parts throughout the several views—

Figure 1 is a vertical end view of mechanism illustrating this invention in its preferred form;

Figure 2 is a plan view of the same mechanism;

Figure 3 is a sectional detail view through the center of the coal feeding apparatus;

Figure 4 is a vertical end view, certain parts being shown in section, on the line 4—4 of Figures 1 and 2;

Figure 5 is a perspective view of the regulating apparatus removed from the other parts of the device; and

Figure 6 is a face view of the adjusting mechanism centered at shaft 30.

Figure 1 shows diagrammatically a furnace 10 having leading into it a pipe 12, through which a mixture of fuel to be consumed and air is propelled by the mechanism of this invention, for the purpose of burning

the same in the furnace by methods not entering into this invention. This pipe 12 is connected at 14 to the upper or discharge end of the main air pipe 16 of the machine of this invention, which pipe is supplied with air by a blower 18 of conventional form driven through belt mechanism 20 by any suitable source of power such as an electric motor 22. In pipe 16 and supported on base 24, is an air control valve mechanism 26 including a rotatable valve 28, pivoted on shaft 30, the same being the subject matter of my earlier patent application, Serial No. 314,136, patented June 5, 1923, No. 1,457,521. By properly rotating this valve member 28, the amount of air delivered by the fan to pipe 16 and thence to pipe 12 is controlled. The outer end of shaft 30 carries a lever arm 32 on which is reciprocatably mounted the cross head 34 selectively adjustable as to position along the lever by any suitable means, such as set screw 36. Pivotedly mounted on this cross head 34 is a horizontally extending lever arm 38 preferably, but not necessarily, made extensible by being made in two pieces adjustably securable together by the bolts 40 of conventional form slidably mounted in elongated slots 42 in each of the slidable parts of this lever. Pivotedly mounted at the end of the outer section of this lever 40 at 44 is the upper end of a bell crank arm 46 pivoted at 48 on a stationary support 50 conveniently mounted on the machine. The second arm 52 of the bell crank, of which arm 46 is a member, is pivotally connected at 54 to a bracket 56 carried on a lever 58 pivoted to a stationary support at 60 and adapted to be selectively controlled by adjusting weights 62 and 64 slidable along the rod. This lever 58 is automatically moved up and down by the action of a diaphragm regulator 66 of conventional commercial construction, whose upper end 68 carries a piston rod 70 attached to the lever 58 at 72. This diaphragm regulator is connected up, by mechanism such as air pipes 73 and 75 not entering into this invention, to suitable automatic or manual control apparatus. When the diaphragm regulator 68 moves the lever 58 upward or in a counter-clockwise direction about pivot 50, it rocks bell crank 46—52 to move lever 32 and consequently

valve 28 in a clockwise direction, as viewed in Figure 5, and the parts move in the opposite direction when the lever 58 moves downwardly.

5 The end of valve mechanism 26 is provided with a graduated scale 74 engaged by a pointer 76 on shaft 30 to indicate to the operator the position of the valve.

10 The adjustment which is obtained by shifting the length of rod 38 through the action of bolts 40 may be accomplished by loosening the set screw 78 on shaft 30 and thus shifting the angular position of lever 32 with reference to shaft 30. This angular 15 adjustment is necessary in order to properly position the initial opening of the valve 28. By loosening the nut 36 and moving the cross head 34 along lever 32, the amount of 20 opening of the valve in proportion to the arc of movement of the bell crank 46—52 is varied, thereby controlling the amount of air delivered with a given movement of lever 58.

25 The main frame 24 of the machine sustains an enclosed casing 80, terminating at its top in a fuel material hopper 81. The bottom of this casing 80 is provided with a horizontally extending passageway 82 leading through a port 84 into the pipe 16. Extending horizontally across pipe 16 and 30 through this passage 82 is a horizontally disposed rotatable shaft 86 carrying rigidly attached thereto a disk 88 and a feed screw 90. Fuel material delivered from hopper 81 to this screw 90 is, when the screw is rotated, 35 moved to the left as viewed in Figure 3, against the disk 88 which breaks up any particles of powdered material which tend to hang together and delivers them through the narrow passage 92 between this disk 88 and 40 the adjacent portion of the wall of pipe 16, all of which is more fully shown, described and claimed in my previously filed application, above identified.

45 Shaft 86 is pressed to the right against wheel 114, hereafter described, by a spring mechanism 94 adjustably controlled by a screw cap 96 on a tubular member 98 attached to a fixed stud 100 on the side of pipe 16 by any suitable means, as for instance the screws 102.

50 Special attention is called to the construction of the right hand end of the screw 90, which, as shown, is recessed at 104 immediately adjacent to the shaft 86 and the closing head 106 in which it is journaled so that there is an annular ridge 108 formed on the end of this shaft, but clear of the head 106, the result of this construction being that powdered material from the hopper 81, descending into the space 104, is, when it gets down to the extreme bottom space 110, below the screw, taken up by the screw threads and transferred with the screw to the left over into passage 16, thus doing away with the binding of the screw and shaft at this

50 point, which experience has demonstrated takes place when this construction is not used.

At the outer right hand end of shaft 86 is a friction drive disk 112 of conventional 70 form, on whose face travels a conventional friction wheel 114 carried on a transverse shaft 116 through the agency of a spline 118 which enables this wheel to reciprocate lengthwise of the shaft, but compels it to 75 rotate with the shaft. This shaft 116 is driven by any suitable means, such as a belt 120 from the fan shaft 122.

80 The wheel 114 is embraced by arms 123 sliding on shaft 116 and rigidly mounted on a rod 124 connected at 126 with an arm 128 of a bell crank whose opposite arm 130 is actuated by rod 132 attached to the lever 58 heretofore fully described. This bell 85 crank is supported by bracket 133. The result of the construction just described is that when the regulator mechanism 66 moves lever 58 upwardly rod 124 and consequently wheel 114 is moved to the right, as viewed in Figure 5, thus moving the wheel 114 to the outer circumference of disk 112, thereby 90 slowing up the speed of the screw 90 and consequently reducing the amount of fuel fed from hopper 81 through passage 92 into pipe 16, the opposite result obviously occurring 95 when lever 58 moves downwardly or in a clockwise direction as viewed in Figure 5.

100 Rod 124 preferably but not necessarily carries an indicating pointer 128 adapted to travel along an indicating scale 130 suitably graduated by calibration or otherwise so that the operator can, by looking at this scale, determine in the first instance the position of wheel 114 on disk 112, but more practically the amount of coal which is being fed 105 by the machine.

110 In actual complete operation of the device, the operator starts the motor 22 to feed coal and send air through passage 16 in the manner described, and as this operation takes place the regulator 66 operates to move lever 58 up and down, as heating conditions taken care of by the apparatus require, thus changing the amount of coal and consequent 115 amount of air delivered into pipe 16 for the proper operation of the apparatus. It is entirely obvious that the one movement of the single member 58 controls the air and coal in unison.

120 It is understood from the adjustment previously described that the operator adjusts the lever mechanism 32—38 to control the point of opening of valve 28 and the proportion of air delivered to the amount of coal delivered, as quality or condition of coal 125 may require.

What I claim is:

130 1. In mechanism of the class described, a fuel conduit, a conveyor for delivering pulverized fuel within the conduit, a vari-

able speed driving device for the conveyor including a slidably adjustable element for effecting variations in the rate of speed of the conveyor, means for forcing a current of air through said conduit, a rotary valve adjustable on an axis parallel to the direction of sliding movement of said element to regulate the amount of air passing through said conduit, and a common means for simultaneously effecting adjusting movement of the element and valve in either direction.

2. In mechanism of the class described, a fuel conduit, a conveyor for delivering pulverized fuel within the conduit, a variable speed driving device for the conveyor including a slidably adjustable element for effecting variations in the rate of speed of the conveyor, means for forcing a current of air through said conduit, a rotary valve adjustable on an axis parallel to the direction of sliding movement of said element to regulate the amount of air passing through said conduit, an operating lever moving in a plane transverse the direction of movement of said element and the axis of the valve, and connections between said element and valve and

said lever whereby movements of the lever will effect simultaneous movements of adjustment of the element and valve.

3. In mechanism of the class described, a fuel conduit, a conveyor for delivering pulverized fuel within the conduit, a variable speed driving device for the conveyor including a slidably adjustable element for effecting variations in the rate of speed of the conveyor, means for forcing a current of air through said conduit, a rotary valve adjustable on an axis parallel to the direction of sliding movement of said element to regulate the amount of air passing through said conduit, said valve including a radial operating handle, a pivoted operating lever, connections between said lever and said element, and connections between said lever and handle including members connected together for lengthwise adjustment, one of said members having adjustable connection with the radial handle of the valve.

In witness whereof, I have hereunto subscribed my name.

AUBREY J. GRINDLE.
